CHANGE MAKING MACHINE

Original Filed Jan. 31, 1923 2 Sheets-Sheet 2

UNITED STATES PATENT OFFICE

CHARLES E. CHALMERS, OF NEW YORK, N. Y.

CHANGE-MAKING MACHINE

Application filed January 31, 1923, Serial No. 616,205. Renewed May 29, 1930.

In my copending application, Serial No. 613,076 filed January 16, 1923, I have illustrated, described and claimed an improved change making machine, more particularly 5 designed and constructed to be used on street cars or similar vehicles where a fare is charged, which machine is under the sole control of the motorman. However, it is not limited to such use, but may be readily employed in other relations where a change making machine is desired or necessary. One of the more important objects of the invention of that application is to provide an improved change making machine of compact and simple construction which is not only adapted to receive the exact fare, but likewise adapted to return the necessary change whenever the passenger deposits a coin therein of a denomination higher than the price of the fare. In 10 that application I have, among other things, illustrated and described a chute for receiving the deposited coins, the same being an expedient employed in conjunction generally with machines of this character. Mechanism 15 is provided in that machine for enabling the inspection, selection and rejection of coins of different denominations, the construction and arrangement being such that the selectors when operated in one direction, enable the 20 coin to be received in the machine, and when operated in the other direction, to be ejected therefrom. Or, stated more generally, the coin selecting means arrests the coin in the 25 course of its travel beyond the chute, and is so related to the chute that the coin may be readily removed in case it is found to be spurious. If the coin is genuine, the coin arresting and selecting means is actuated to deposit the coin at a certain position in the 30 machine so as to enable the latter to be operated through the intermediary of said coin. For a more detailed description of this machine, reference is hereby made to the said copending 35 application.

40 In my copending application, Serial No. 613,077 filed January 16, 1923, there is illustrated, described and claimed among other things, the provision of mechanism for receiving one or a multiple of fares from a coin 45 deposited in the machine, suitable provisions

being also made in connection therewith for registering the number of fares taken from said coin, or, more broadly stated, for registering the net amount of cash received by the machine.

55 In my copending application first above referred to I have illustrated, described and claimed change carriers provided with a plurality of magazines or pockets which are movably supported in the machine. In the second copending application above referred to, the invention comprises, among other things, an improvement over the first mentioned application, although not limited thereto, in 60 that the magazines or pockets are preferably stationary, and in connection therewith, provision is made for extracting one or a multiple of coins from the same magazine depending upon the number of fares to be taken from the particular coin deposited. For a more 65 detailed statement of the construction, objects, features and advantages of the second mentioned application, reference is hereby made thereto.

70 The present invention is an improvement 75 upon my inventions illustrated, described and claimed in my two copending applications above referred to, and resides chiefly in the feature of providing a plurality of improved coin chutes fully equipped with 80 mechanism for enabling spurious coins or slugs to be readily detected and ejected from the machine. In connection with the ejecting instrumentalities mechanism is employed 85 for registering the number of coins ejected from the machine. It has been found that where slugs have been deposited, they are invariably of a size corresponding more or less to the size of standard coins. In the 90 device illustrated herein, I have therefore shown mechanism which enables the operator to eject slugs of the size more or less equivalent to the size of fifty, twenty-five, five and ten cent pieces, irrespective of which chute 95 the particular slug is dropped into.

100 Counters are so arranged adjacent to the various chutes to indicate or register the size and number of slugs ejected. One of the more important features of the invention of the present application over the devices

of my copending applications above referred to resides in the means controlled by the operator for directing the lowermost coin in said chutes at will either into a passage-
 5 way leading the same to an operative position in the machine, or into a passageway to enable the return of the coin deposited, and simultaneously operated means for arresting the movement of the succeeding
 10 coin or coins that happen to be deposited in the chute, thereby avoiding the danger of jamming the machine. This means for arresting the movement of the succeeding coin or coins in the chute is so constructed and
 15 arranged that it will function irrespective of the sequence or mistakes made in depositing the particular coin in the proper chute. For instance, this device will function even if a ten cent piece or a plurality of ten cent
 20 pieces are deposited in the five, twenty-five or fifty cent chutes, thus enabling the improper coin deposited to be returned to the passenger.

Another feature of this invention, aside
 25 from its compact form and simplicity of operation, resides in the ability of the invention to be applied to change making machines of general application and use.

Another of the more important features
 30 of this invention is the fact that change may be simultaneously made by the machine from a plurality of coins. In other words, change may be made simultaneously for a ten cent, twenty-five cent, and a fifty cent piece de-
 35 posited in the machine, thus greatly expediting or facilitating the handling of the passengers boarding the street car, or vehicle, as the case may be.

Other objects, advantages and features of
 40 the construction will be more clearly apparent from the detailed description below taken in connection with the accompanying drawings, in which:

Fig. 1 is a front view of the change making
 45 machine showing the application of my im-
 provements thereto.

Fig. 2 is a vertical section taken on the
 line 2—2 of Fig. 1.

Fig. 3 is a fragmentary vertical section tak-
 50 en at right angles to the section illustrated
 in Fig. 2, and passing through one of the
 coin chutes. The parts are illustrated in
 position to show the method of ejecting a coin
 from the machine.

Fig. 4 is a view similar to Fig. 3 showing
 55 the relative location of the parts enabling
 the coins to be received into the machine.

Fig. 5 is a fragmentary section taken on
 the line 5—5 of Fig. 2.

Fig. 6 graphically illustrates the condition
 60 where, for instance, a ten cent piece has been
 accidentally deposited in the fifty cent coin
 chute.

Referring to the drawings in detail, the ref-
 65 erence numerals 10 and 11 designate cooper-

ating members which define the coin chutes
 12, 13, 14 and 15 for the initial reception
 of ten, five, twenty-five and fifty cent pieces
 respectively. These two members 10 and 11
 also constitute the front wall of the machine,
 70 the top of which is indicated in part by the
 reference numeral 16 (see Fig. 2). The top
 is provided with a suitable closure 17, pivoted
 or otherwise secured thereto to enable access
 to the mechanism (not illustrated) enclosed
 75 in the upper part of the machine. This top
 portion 16 and the closure 17 are substantially
 the same in all essential respects to the cor-
 responding parts described and illustrated in
 my copending applications above referred to.
 80 The same is true with respect to the main
 shaft 18, operating crank 19, slotted members
 20 and 21, bars 22 and 23, studs 24 and 25,
 crosshead 26 connecting the bars 22 and 23,
 and the operating fingers 27, 28, 29 and 30.
 85

The construction of the coin chutes 12, 13,
 14 and 15 and their associated mechanism
 are substantially the same one with respect
 to the other, except insofar as I will more
 90 specifically point out in connection with
 chute 15 to take care of a condition which
 is illustrated in Fig. 6. Consequently, it is
 only necessary to describe in detail the con-
 struction and mode of operation of one of the
 95 coin chutes, and for this purpose I have se-
 lected that one indicated by the reference
 numeral 15. The coin chute 15 is formed, in
 the embodiment of the invention illustrated,
 by the inter-relation of the wall members 10
 and 11, the latter of which is clearly illus-
 100 trated in Figs. 1 and 5, and is defined in part
 by a bevelled transparent member 31 held in
 a correspondingly shaped opening therein by
 means of a suitable clamping member 32.
 The width and thickness of the coin chute in
 105 this particular instance corresponds exactly
 to the diameter and thickness of a fifty cent
 piece so that the latter passes freely there-
 through. In the instance shown, the chute
 itself is deep enough to receive four coins,
 110 but it will be understood that the coin chute
 may be made of any depth desired to receive
 any number of coins. Located immediately
 below the coin chute 15 is a member 33 adapt-
 115 ed to be rocked manually by the operating
 handle 34. The member 33 is mounted upon
 the oscillating pintle 35, (see Fig. 2). In
 alignment with the coin arresting member 33
 is a vertical wall 36 located in a plane pass-
 120 ing midway between the walls 37 and 38 of
 the chute, and offset from the walls 37 and
 38 are two walls 39 and 40. The walls 36
 and 39 define a passageway 41 leading to
 a return tray 42, whereas the walls 36 and
 125 40 define a passageway 43 which conducts
 or delivers the coin into operative position
 in the machine in front of the plunger 27.
 It will therefore be seen that when the mem-
 ber 33 is rocked in a clockwise direction, as
 130 illustrated in Fig. 3, the lowermost coin in

the chute is returned or rejected from the machine. When the member 33 is rocked in a counterclockwise direction, as illustrated in Fig. 4, the coin will be delivered into an operative position within the machine.

Mechanism is provided for automatically maintaining the member 33 in a substantially vertical position for the purpose of arresting the coins in the coin chute, and for this purpose I preferably employ a spring 44 (see Fig. 2) the lower end of which is connected to a stud 45 and the upper end of which is connected to a lug 46 projecting downwardly from the pintle 35. The spring 44 is located substantially in a vertical plane which passes through the intermediate wall 36. Consequently, the spring exerts a downward pull in a vertical direction upon the stud 46, thus automatically maintaining the member 33 in a vertical position. As clearly illustrated, the member 33 and the downwardly projecting lug 46 extend in opposite directions from each other and from the pintle 35.

If suitable provisions were not provided therefor, all of the coins in the coin chute would drop into one or the other of the passageways 41 and 43 leading from said chute upon the movement of the coin arresting member to the right or left as illustrated in Figs. 3 and 4. To avoid this I have provided a slide 47, having a slot 48 therein, slideable back and forth across the coin chute and located a distance from the bottom of said chute approximately corresponding to the diameter of the coin in the particular chute. The slide 47 is equipped with a rearwardly extending arm 49 projecting through a slot in the wall member 10 and adapted to be engaged by the resilient members 50 and 51 (see Fig. 5) which are connected to the pintle 35 and are so constructed and arranged that when the pintle is operated in a clockwise or counterclockwise direction, said resilient members will coat with said arm 49 to actuate the slide 47. The normal position of this slide 47 is clearly indicated in Fig. 1, with the slot 48 therein registering with the coin chute passage so as to enable the coins to pass therethrough. When the member 33 is operated in a clockwise direction, a substantially corresponding movement is imparted to the slide 47 bringing one of the unslotted end portions of the slide into the path of the next succeeding coin, thus preventing the latter from being discharged simultaneously with the lowermost coin in said chute into the return passageway 41. If the coin arresting member 33 is operated in a counterclockwise direction, a substantially corresponding movement will be imparted to the slide 47 in a direction opposite to the direction previously described, bringing the other unslotted end portion of the slide into the path of the next succeeding coin in the coin slot, thus enabling only the lowermost

coin in the coin slot to be delivered to its operative position within the machine.

I have previously referred to a certain condition which is inherent in the embodiment of the invention illustrated, due to the accidental deposit of a coin of one size into a chute for the reception of coins of increased sizes. There is no coin in use smaller in size than the ten cent piece, consequently, the slideable member may be and is preferably located at a distance from the upper end of the coin arresting member 33 equal to the diameter of that coin. For the same reasons, the slideable member 47 employed in connection with the five cent piece and the twenty five cent coin deposited, may be located at a distance from the upper end of the coin arresting member 33 equal to the respective diameter of these coins. However, this is not true with respect to the fifty cent coin chute, because of the relative diameters of the ten cent and fifty cent pieces. In other words, if the slideable member 47 be located at a distance from the upper end of the coin arresting member 33 equal to the thickness of the fifty cent piece, it will be readily seen that if a ten cent piece is accidentally dropped into the said fifty cent coin chute (see Fig. 6) the next coin, say a fifty cent piece, would pass sufficiently far through slot 48 as to militate against the effective operation of the slideable member 47, or may even pass through said slot upon the actuation of the coin arresting member 33 in either direction. Consequently, I locate the slideable member 47 in this particular instance in a plane somewhat below the upper edge of the lowermost fifty cent piece in the chute, as clearly illustrated at the left hand side of Fig. 1. In other words, the slideable member 47 so far as the fifty cent coin chute is concerned, is located at a distance from the upper end of the coin arresting member substantially less than the diameter of the coin itself.

In my copending applications above referred to I have illustrated and described suitable means for counting the net amount of coins received by the machine. This is accomplished by the operation of the machine to return change and to receive the fare. It is desirable to record the number of bad coins deposited and rejected from the machine and this I do in the present embodiment of my invention preferably by causing a stud 52 on the slide 47 to engage with and actuate the spring-pressed arm 53 of a suitable counter 54 whenever the coin arresting member 33 is actuated in a clockwise direction to eject the coin from the machine.

From the foregoing it will be seen that a plurality of coins may be deposited in each of the coin chutes 12, 13, 14 and 15; that coins can be received or rejected in any order from any one of said chutes independently of the other; that it enables the location at the same

time of one coin of each denomination in operative position in the machine with the result that change may be simultaneously returned for a plurality or all of said coins; that the device as a whole is of very compact form; that the construction is simple, cheap to manufacture, and not liable to get out of order; and that the invention is adapted to be employed generally with change making machines. It will therefore be seen that the device is particularly desirable and advantageous in the expeditious handling of a large number of passengers, thus avoiding congestion about the machine and the inevitable delay incident thereto.

I have illustrated and described herewith what I regard as the preferred embodiment of my invention, but it is to be expressly understood that I do not limit myself thereto, as many changes may be made in points of detail and other embodiments resorted to without deviating from the true spirit and scope of my invention.

What I claim is:

1. A change making machine comprising a chute for receiving a plurality of deposited coins, a stationary passageway leading from said chute to enable the coins to be received into the machine, a second stationary passageway to enable the return of the coins deposited, means controlled by the operator for directing the lowermost coin in said chute into either of said passageways, and simultaneously operated means for arresting the succeeding coins in said chute.

2. A change making machine comprising a coin chute for successively receiving a plurality of coins, a passageway for conducting the coins from said chute to their operative positions in the machine, a stationary passageway for conducting said coins directly from said chute to the exterior of the machine, means for arresting the coins in said chute to enable them to be inspected, means for actuating said arresting means to enable the lowermost coin in said chute to be discharged into either of said passageways, and simultaneously actuated means for arresting the movement of the succeeding coin or coins in said chute.

3. A fare collecting and change making machine comprising a chute for holding a plurality of coins, in combination with means for successively feeding said coins from said chute into the machine, and means for rejecting any of the coins in said chute.

4. A fare collecting and change making machine comprising a chute for receiving a plurality of deposited coins, a passageway in a plane with said chute and leading from the latter to enable the coins to be received into operative position in the machine, a second passageway in a plane with said chute to enable the return of the coins deposited, pivoted means normally located between said

passageways and controlled by the operator for directing the lowermost coin in said chute into either of said passageways, and simultaneously operated means for arresting the succeeding coins in said chute.

5. A fare collecting and change making machine comprising a coin chute for successively receiving a plurality of coins, a passageway in a plane with said chute for conducting the coins from said chute to their operative positions in the machine, a second passageway in a plane with said chute for conducting said coins directly from said chute to the exterior of the machine, pivoted means normally located between said passageways for arresting the coins in said chute to enable them to be inspected, means for actuating said arresting means to enable the lowermost coin in said chute to be discharged into either of said passageways, and simultaneously actuated means for arresting the movement of the succeeding coin or coins in said chute.

6. A change making machine comprising a plurality of coin chutes each adapted to hold a plurality of coins, a stationary passageway for each of said chutes for conducting coins from the latter to their operative position in the machine, a stationary passageway for each of said chutes for conducting coins directly from said chutes to the exterior of the machine, means for arresting the coins in said chutes to enable them to be inspected, and means for actuating said arresting means to enable a predetermined number of the lowermost coins of the plurality in each chute to be discharged into said passageways.

7. A change making machine comprising a chute for receiving a plurality of deposited coins, a stationary passageway leading from said chute to enable the coins to be received into the machine, a second stationary passageway to enable the return of the coins deposited, means controlled by the operator for directing a predetermined number of the lowermost coins of a plurality of coins in said chute into either of said passageways, and simultaneously operated means for arresting the succeeding coins in said chute.

8. A fare collecting and change making machine comprising a chute for receiving a plurality of deposited coins, a passageway leading from said chute to enable the coins to be received into the machine, and a second passageway to enable the return of the coins deposited, in combination with means controlled by the operator for directing the lowermost coin in said chute into either of said passageways, and simultaneously operated means including a slide member movable transversely of said chute for arresting the succeeding coins in said chute.

9. A fare collecting and change making machine comprising a chute for receiving a plurality of deposited coins, a passageway

leading from said chute to enable the coins to be received into the machine, and a second passageway to enable the return of the coins deposited, in combination with means for arresting said coins in said chute to enable them to be inspected, means for actuating said arresting means to enable the lowermost coin in said chute to be directed into either of said passageways, and means, including a slide member movable transversely of said chute, resiliently connected to and simultaneously actuated by said actuating means for arresting the movement of the succeeding coin or coins in said chute.

10 10. In a fare collecting and change making machine, a chute for receiving a plurality of deposited coins, a passageway leading from said chute to enable the coins to be received into the machine, and a second passageway to enable the return of coins deposited, in combination with means for arresting said coins in said chute to enable them to be inspected, means for actuating said arresting means to enable the lowermost coin in said chute to be discharged at will into either of said passageways, and simultaneously operated mechanism for arresting the succeeding coins in said chute, said mechanism comprising a slide movable transversely of said chute and provided with a slot therein normally registering with the passageway of the chute and through which slot the coin is adapted to pass, and means for operatively connecting said actuating means and said slide.

20 11. In a fare collecting and change making machine, a chute for receiving a plurality of deposited coins, a passageway leading from said chute to enable the coins to be received into the machine, and a second passageway to enable the return of coins deposited, in combination with means when in normal position for arresting said coins in said chute, means for actuating said arresting means at will in opposite directions from normal position to enable the lowermost coin in said chute to be discharged into one or the other of said passageways, spring actuated means for automatically returning said arresting means to normal position, and mechanism simultaneously operated by said actuating means for arresting the succeeding coin or coins in said chute, said mechanism comprising a slide member movable transversely of said chute and provided with a slot therein normally in register with the passageway of the chute and through which slot the coin is normally adapted to pass into engagement with the first mentioned arresting means, and a connecting means between said actuating means and said slide.

30 12. In a fare collecting and change making machine, a chute for receiving a plurality of deposited coins, a passageway leading from said chute to enable the coins to be re-

ceived into the machine, and a second passageway to enable the return of coins deposited, in combination with a pivoted member normally arresting said coins in said chute, means for actuating said member at will in opposite directions from normal position about said pivot as an axis to enable the lowermost coin in said chute to be directed into one or the other of said passageways, spring actuated means for automatically returning said member to normal position, and mechanism simultaneously operated by said actuating means for arresting the succeeding coin or coins in said chute, said mechanism comprising a slide member movable transversely of said chute and provided with a slot therein normally in register with the passageway of the chute and through which slot the coin is normally adapted to pass into engagement with said arresting member, and a resilient connecting means between said actuating means and said slide.

In testimony whereof, I have hereunto set my hand this 26 day of January, 1923.

CHARLES E. CHALMERS.
